AIR CONDITIONING APPARATUS

Charles B. Grady, West Orange, N. J.

Application November 15, 1935, Serial No. 49,869

6 Claims. (Cl. 257—7)

This invention relates to air conditioning apparatus, adapted for the treatment of air in one or more of the following respects, namely cleaning or filtering it, modifying its temperature or cooling it, and controlling its moisture or humidifying it and medicating it. The apparatus is useful for example for the conditioning of air in dwelling or other rooms, including automobile or trailer interiors. As specifically herein shown the apparatus is especially of utility in summer to cool and clean, and to humidify or dehumidify the air of closed cars or rooms, such as sleeping rooms occupied for example by persons subject to hay fever, pollen asthma and similar afflictions. The great value of this treatment and apparatus for such patients is that while indoors, especially through each night, and while motoring over long distances, extensive recovery from the trouble may be effected and the resistance built up to such high point that a reasonable amount of daily outdoor exposure to the pollen and other conditions, and even strenuous exercise and exertion, may be had without trouble. The apparatus however is universal in its adaptation to advantageous use in winter by changes in operation and control.

I have already shown gas treating or air conditioning apparatuses in several patents and pending applications, namely, Patents No. 2,004,103 of June 11, 1935, and No. 2,013,270 of September 3, 1935, and applications, Serial Nos. 713,086 filed February 27, 1934 Pat'd Dec. 1, 1936, No. 2,062,412 and 732,958 filed June 29, 1934, Pat'd Dec. 1, 1936, No. 2,062,413, to which reference may be had for various details not herein fully disclosed; and the present invention may be considered as an improvement on the apparatuses of said prior patents and applications.

For the purposes thus outlined the objects of the present invention are to afford a practical, compact, quiet and relatively inexpensive apparatus adapted for use in automobiles, dwellings and elsewhere for the conditioning of air in closed rooms or spaces in an efficient and economical manner. Another object is to render the system convenient in operation and regulation and readily adaptable to use in winter or summer. A further object is to enhance safety as against escape of refrigerant into the conditioned air; and another object to render the system usable for a closed automobile, and operable from its power plant, and to afford safety to the occupants from refrigerant or CO gases. Other and further objects and advantages of the invention will be explained in the hereinafter following description of an illustrative embodiment of the invention or

will be apparent to those conversant with the subject.

To the attainment of such objects and advantages the present invention consists in the novel air conditioning apparatus and the novel features of combination, arrangement and construction herein described or illustrated.

In the accompanying drawings, Figure 1 is an elevation view, partly broken away, looking toward the right hand side of an automobile 10 containing apparatus for conditioning the air contained in the interior room or space, embodying this invention.

Fig. 2 is a partial rear elevation of the same on a larger scale and broken away to show interior 15 construction.

Fig. 3 is a partial right elevation in section taken substantially on the section line 3—3 of Figs. 2 or 5.

Fig. 4 is a left elevation in section taken substantially on the line 4—4 of Figs. 2 or 5.

Fig. 5 is a partial top plan view broken away to show the interior construction.

Fig. 6, in right elevation and section, shows a detail of Fig. 3 on larger scale.

Fig. 7 is a front elevation of the engine and adjacent elements.

Fig. 8 shows a modified apparatus in top view, partially in section on the line 8—8 of Fig. 9, wherein the principles of the invention are applied to the conditioning of air in a room of a building.

Fig. 9 is an exterior elevation view of the apparatus shown in Fig. 8.

Fig. 10 is a right hand elevation in section of the same apparatus taken substantially on the line 10—10 of Fig. 9.

Fig. 11 is a detail interior elevation view of certain regulating and adjacent devices of Figs. 8 to 10.

Referring first to the automobile embodiment shown in Figs. 1 to 7, it is to be understood that the principles illustrated are applicable to other types of vehicles, or even to stationary enclosures or rooms. The automobile body 15 is shown as provided with a built-in rear trunk or extension 16, exterior to the body and having compartments for general purposes and others for the elements of the present invention. At the front is conventionally indicated the usual engine 17, and as shown in Figs. 1 and 7 the engine shaft carries the usual pulley 18 with the belt 19 driving the pulley 20 of the fan 21 used for engine cooling purposes. The belt 19 is shown also as 55

extending around the pulley 22 of a generator 23, serving ignition purposes.

As a convenient source of temperature modifying or cooling for the purposes of the present invention the belt 19 is shown extending also around the pulley 24 of a compressor or gas pump 25, with a clutch or coupling 26 for throwing the compressor into and out of action. As will appear further the compressor 25 is one of the elements of a refrigerating system, driven by the automobile engine, a refrigerant medium, as sulfur dioxide, being supplied to the compressor through a pipe or passage 28, compressed therein, and delivered through a pipe 29.

With the specific arrangement shown in Figs. 1-7 a compact and serviceable conditioning service is afforded, the compression refrigerating system being illustrated, and the compressor thereof being located at the forward part of the car, and operated by the engine as described. For convenience the remaining elements of the refrigerating system may first be traced and identified, before describing the means of handling and treating the air. Thus the pipe 29 from the compressor 25 extends rearwardly to a condenser or air cooled coil 31, which however might be located adjacent the car radiator and fan. The pipes 28 and 29 may be flexible copper tubes and disposed in any convenient manner between the compressor and the elements of the rear of the car, a particular arrangement being indicated in a diagrammatic way on Fig. 1. The condenser 31 is shown in the form of a radiator, with successive horizontal pipes trending preferably downwardly through an air circulation chamber 36. Beyond the cooler or radiator 31 the refrigerating passage extends first to a check valve 32, at the left side, preventing possible back flow. From the check valve the passage next extends to an expansion valve 33, representing any device through which the refrigerating medium flows from a condition of high pressure to a condition of low pressure, the medium usually liquidifying within the condenser and vaporizing beyond the expansion valve. From the expansion valve the refrigerating passage extends through a system of cooling coils 34 immersed by either partial or complete submergence in a heat transmitting fluid, preferably water, as will be further described. The cooling coils trend from the left to the right hand side of the car and thence deliver into the return pipe 28 through which the warmed vapor is conducted back to the compressor 25. The coils 34 are not complete convolutions but are preferably of U-shape in end view as seen in Figs. 3 and 4, but the last portions 35 of these coils are merely horizontal, being below the compartment 41.

The cooling of the radiator or condenser piping 31 is shown as effected in a narrow vertical air chamber 36 enclosing the radiator, to the rear of the trunk, as best seen in Figs. 3 to 5. The left end of the condenser compartment 36 has an air inlet 37 provided with louvers, while near the right end of the compartment is an electrically driven fan 38 propelling the air outwardly through a rear exit, thus maintaining a forced air circulation to cool the pipes 31 and condense the refrigerant therein, although natural draft in some cases might be sufficient.

Referring next to the general elements, the trunk 16 is shown mounted fixedly at the rear of the car and as having an openable cover 39 below which is an empty compartment 40 for general use, the accommodation of tools, personal

belongings, etc. In the lower right part of the trunk is shown a smaller compartment 41 arranged to receive some of the refrigerating effect, and having an exterior side door 42 whereby foodstuffs and other articles may be placed in 5 the compartment and therein kept cool.

Below the general compartment 40 is shown a false bottom 43 and at the sides false left and right walls 44 and 45, all of which are shown as protected by suitable insulating material, which 10 also may be placed elsewhere as desired. At the bottom portion of the trunk, for its full width, is shown a water compartment or tank 46 substantially filled with water 47 that constitutes a heat transmitting means between the expansion 15 or cooling coils 34 and the air duct 56 to be described. A non-freezing liquid may be used, as water mixed with suitable agents, oil etc.

Referring next to the handling of the air, this consists principally of a recirculation of air from 20 the room within the car body but supplemented to a minor but progressive extent by the introduction of fresh quantities of outside air. From the inside space of the car is shown an air outlet 50 at the upper right rear corner, this being bent 25 downwardly as a downtake 51 which leads to a vertical port 52 between the car body and trunk. The port 52 conducts the outgoing air into a chamber 53 containing an electrically driven fan 54 by which pressure and circulation are maintained. The fan chamber 53 may be insulated as shown. From the fan chamber extends air downtake 55, located at the left side of the cooling compartment 41. The downtake 55 delivers into an immersed air duct 56 either fully or partly 30 submerged in and extending, preferably horizontally, through the cooled water 47 in the tank 46. The air duct is closed and the air to be treated is thus kept from contact with the water and wholly isolated from the refrigerating system. 35 The heat in the air is readily taken up by the duct walls and passes into the body of water 47 and from thence is absorbed by the refrigerating agent in the coils 34. On account of probable condensation in the air duct 56 it is shown as 40 provided with a small downtake 57 controlled by a drip cock 58, for continuous or periodic discharge of condensate.

From the left end of the immersed air duct 56 is an uptake air passage 59 which is shown 50 thoroughly insulated, and this uptake leads to a port 60 between the trunk and body of the vehicle. Within the body is a continued uptake 61 leading to an air inlet 62 discharging preferably in a forward direction at the upper left rear corner of the enclosed space. Thus conditioned air is continuously supplied to the occupants, the air moving with gentle circulation through the space and the stale air being drawn out at the opposite corner for recirculation and reconditioning.

In order to supply a fractional proportion of fresh air there is shown, behind the air inlet 62 which leads into the car, an exterior fresh air intake 65 wherein is interposed a filter 66 of fibrous 65 or other material, excluding pollen and other undesirable solids or gases. To maintain the desired inflow an electrically driven fan 67 is shown in front of the filter 66, sucking in the air and discharging it directly into the inlet pipe 62; or the 70 inlet 62 and fan may deliver instead into the air outlet, for conditioning before reaching the car space. By the use of inlet 62 and fan a slight excess of pressure is maintained within the enclosed space. The result is that adjacent the 75

doors, windshield and floor there will be a constant slight outflow through any cracks or crevices. This gradually disposes of excess stale air but additionally performs the function of preventing the intake of harmful gases such as carbon monoxide which it is known frequently enters the car space through the bottom boards and otherwise.

Air filters may be located elsewhere, as at 68, 10 near the fan chamber 53, for cleansing recirculated air; and these filters may be kept moist or specially treated to remove or neutralize injurious elements as carbon monoxide. Also the circulating air may be treated by medication or given 15 an aroma, as by introducing an agent, as pine needle oil, into the air duct or passages or at the filters.

Figs. 8 to 11 show the principles of this invention applied to the conditioning of air in a room 20 or space within a stationary structure or building. The apparatus may care for several rooms, only one being shown. The room is bounded by walls 70, and exterior of the building is shown a box or trunk 71 containing much of the apparatus hereof. Pipes 73 may carry refrigerant or other cooling fluid to and from the apparatus, the source of cold water or fluid being omitted in this embodiment. The cooling or expansion coils 74 are shown as of U-shape, and these, and alternative heating coils 75, are shown immersed in 25 an exterior tank 76 containing water 77. Air to be conditioned passes from the room by air outlet 80 leading into a fan chamber 81 containing an electrically driven fan 82. Descending from the 30 fan chamber the air passes into the right end of the submerged horizontal air duct 84, and at the far or left end of the air duct is shown a horizontal air outtake 85 or duct leading to an uptake 86 extended vertically through the wall 70. This 35 uptake delivers, through an inlet 87, the conditioned air to a high point in the room; but may be arranged to deliver warm air lower down for winter use.

The water connections may be as follows. An 40 upper water outlet pipe 91 is shown extending from the top side of the water tank 76 and leading to waste, in case of overflow or expansion of water in the tank. From the lower part of the tank extends a water drain pipe 93 controlled by 45 a cock 94. Between the pipes 91 and 93 is shown a gage glass 95 by which the depth of water in the tank may be observed, and beyond the valve 94 is a water pipe leading to waste. By adjusting the water depth, causing greater or less immersion 50 of the air duct, the cooling effect upon the circulating air is regulable. When the entire duct is submerged and surrounded by the cold water the air receives much greater temperature drop than when the water level is below the top level 55 of the duct. The gage glass, and the valve 94 therefore give a means of regulation, taken with water supply valve to be described. The water is a transfer medium between the coils 74 or 75 and the air duct and the depth of the liquid gives 60 control of the rate of heat transfer.

As water may accumulate by condensation or otherwise in the air duct 84 there is shown a small drain pipe 97 leading from the lower part thereof, its inlet slightly above the bottom of the duct so 65 as to maintain a small depth of water for humidifying the air, which plan may also be used on the automobile. The drain pipe 97 is shown leading to the waste pipe 96, with a loop constituting a seal protecting the air duct.

70 For the purpose of supplying water to tank 76,

and thereby in cooperation with the outlet cock 94 controlling the depth of water in the tank, and therefore the cooling or heating effect upon the air, there is shown a relatively small water supply pipe 99 leading from a main directly into 5 the tank, the same controlled by a cock 100. This and the other controlling elements are placed on an interior panel as seen in face view in Fig. 11. By opening the cock 100 the water level in the tank may be raised. By closing it and opening 10 the cock 94 the water level may be lowered.

In order to supply water to the air duct for humidifying purposes there is shown a supplemental water pipe 101 leading from pipe 99 directly into the air duct and controlled by a needle valve 102 which should be set to allow a slow supply or drip of water into the duct.

The operation of the invention has been indicated, but may be more fully described as follows. The air to be conditioned is maintained in forced 20 circulation through the conditioning elements, the conditioned air flowing with suitable distribution through the space or room under treatment. One portion of the air passage constitutes an immersed air duct, closed, and submerged partly or 25 wholly in the liquid or water through which the heat transfer is made from or to the air duct. A quite small static body of water is sufficient, this being one of the permanent elements of the apparatus. The air being treated is kept out of 30 contact with the transmitting water and thus safely removed from the refrigerating means. Fresh air is progressively and gradually drawn into the space, through a filter, causing a positive 35 interior pressure and thus causing exclusion of gases at other points. At all seasons the recirculated air and the additional air are cleaned and may be medicated. In hot weather the recirculated air is cooled as described and by reason of the lowering temperature is dehumidified. 40 Condensate in the air duct is drained away to keep dry the duct. The cooling and dehumidifying operations are regulable by varying the depth of immersion of the air duct, by observation, or automatically by thermostat or humidistat control. In cold weather the water may be 45 used for transmitting heat to the recirculated air, by the coils 75 as described in connection with Figs. 8 to 10 and the air may be humidified by maintaining a small quantity of water in the 50 air duct, by the valve 102, its depth restricted by the drain pipe 97. As in hot weather the air temperature is controllable by adjusting the depth of liquid in the tank. The control connections for temperature and humidity regulation 55 are all accessible on the interior panel as shown in Figs. 8, 10 and 11.

Two illustrative embodiments have thus been shown by way of explanation of the principles hereof, but since various matters of combination, arrangement and construction may be modified within the scope of the invention it is not intended to limit the invention to such matters except so far as set forth in the appended claims.

I claim:

1. Apparatus for air-conditioning an enclosed space comprising a tank isolated from the space and holding a body of heat-transferring liquid, an air duct extending through said tank, air passages from the space to the duct and from 70 the duct back to the space, with means forcing air circulation therethrough, means for maintaining the tank liquid at a cooler temperature than the air to be conditioned, and a separate air inlet for admitting outdoor air directly to 75

- said space, with an air filtering device interposed in said separate inlet and a means or fan for drawing air in by said inlet to freshen the air in said space and create a slight excess inside pressure.
2. A passenger automobile fitted with the air recirculating means, liquid cooling means and separate air inlet means of claim 1.
3. A passenger automobile fitted with the air recirculating means, liquid cooling means and separate air inlet means of claim 1, the liquid cooling means comprising a compression refrigerating plant driven mechanically from the engine of the vehicle.
4. Apparatus for air-conditioning an enclosed space comprising a tank isolated from the space and holding a body of heat-transferring liquid, a closed, substantially horizontal immersed air duct extending through said tank and above its bottom, air passages from the space to the duct and from the duct back to the space, with means forcing air circulation therethrough, and means for maintaining the tank liquid at a different temperature from or cooler than the air to be conditioned; the liquid-temperature-maintaining means comprising an elongated pipe arranged in U-shape through the tank with the air duct occupying the space within the U-shape.
5. Apparatus for air-conditioning an enclosed space comprising a tank isolated from the space and holding a body of heat-transferring liquid,

a closed, substantially horizontal immersed air duct extending in a single substantially straight pass through said tank and above its bottom, air passages from the space to the duct and from the duct back to the space, with means forcing air circulation therethrough, and means for maintaining the tank liquid at a different temperature from or cooler than the air to be conditioned; the liquid-temperature-maintaining means comprising an elongated pipe arranged through the tank between the inner surface of the tank and outer surface of the duct in a configuration concave toward the air duct and with the air duct occupying the space within said configuration.

6. Apparatus for air-conditioning the enclosed space within a passenger automobile body, comprising a tank isolated from the space and holding a body of heat-transferring liquid, a closed and substantially horizontal air duct extending through said tank, said body having corner air inlet and outlet at the upper rear sides, and recirculation passages between the space and duct, comprising a downtake air passage from said outlet to the duct and an uptake air passage from the duct to said inlet, with means forcing air circulation therethrough, and means for maintaining liquid in the tank at a different temperature from or cooler than the air to be conditioned.

CHARLES B. GRADY. 30
